UNITED STATES PATENT OFFICE.

HOWARD D. COLMAN, OF ROCKFORD, ILLINOIS, ASSIGNOR TO HOWARD D. COLMAN,
LUTHER L. MILLER, AND HARRY A. SEVERSON, COPARTNERS TRADING AS
BARBER-COLMAN COMPANY, OF ROCKFORD, ILLINOIS.

WASTE-WINDER.

1,262,644.

Specification of Letters Patent. Patented Apr. 16, 1918.

Application filed May 12, 1916. Serial No. 96,977.

To all whom it may concern:

Be it known that I, HOWARD D. COLMAN, a citizen of the United States, residing at Rockford, in the county of Winnebago and 5 State of Illinois, have invented certain new and useful Improvements in Waste-Winders, of which the following is a specification.

When the outer portion of the yarn mass upon a bobbin or other carrier is soiled, cut 10 or tangled, such damaged portion must be removed before the remainder of the yarn can be used in the intended manner. This invention relates to means for unwinding such damaged yarn in order that the remainder 15 of the yarn may be rewound to form yarn masses suitable for use in the subsequent processes employed in the manufacture of cloth.

In the accompanying drawings, Figure 1 20 is a fragmental side elevation of a waste winder embodying the features of my invention. Fig. 2 is a fragmental front elevation of the winder. Fig. 3 is a fragmental sectional view taken in the plane of dotted line 3 of Fig. 1.

The embodiment herein shown of the invention comprises a supporting frame 1 having bearings in which is supported a continuously-rotated drive shaft 2. Upon 30 said shaft is splined a friction clutch member 3 which is arranged to engage a clutch member 4 formed upon a bevel gear wheel 5, the latter being rotatably mounted upon the shaft 2. The gear wheel 5 meshes with 35 a bevel pinion 6 which is fixed upon a shaft or spindle 7 carried in suitable bearings upon the frame 1. The shaft 7 extends forwardly and upwardly and carries at its forward end a frusto-conical core or yarn carrier 8. To prevent yarn from getting into 40 the space behind the yarn carrier 8, the rear end of the yarn carrier is provided with a peripheral flange 9 which rotates within the flange 10 of a disk fixed to the housing 11. Said housing is carried by the frame 1 and 45 comprises a circular rear wall 12 and a peripheral wall 13. At the lower side of the housing 11, the peripheral wall 13 is provided with a slot 14 through which the 50 yarn may be led into engagement with the yarn carrier 8.

The means for sliding the clutch member 3 into and out of engagement with the clutch member 4 may be of any suitable character, as, for example, a treadle 15 connected by means of a link 16 to an arm 17 pivoted at 18 in the frame 1. Rigid with the arm 17 is an arm 19 having a forked upper end carrying antifriction rollers 20 that lie within a peripheral groove 21 in 60 the clutch member 3. Rigid with the arms 17 and 19 is an arm 22 to which is connected a tension spring 23 that normally holds the clutch member 3 out of engagement with the clutch member 4. 24 (Fig. 2) is a stop 65 arranged to be engaged by the arm 17 to limit the action of the spring 23.

If desired, means may be provided for supporting a yarn mass which is to be rewound upon the yarn carrier 8. However, 70 it is usually more convenient for the operative to hold the yarn carrier in her hand while the yarn is being unwound. The yarn is connected to the rapidly revolving yarn carrier 8 by simply looping the end of the 75 yarn around the yarn carrier 8 or laying the yarn upon the mass of yarn on said carrier. The slot 14 is of such limited width that the bobbin if jerked from the hand of the operator cannot reach the yarn carrier 8. 80 The peripheral wall 13 compels the operative to lead the yarn through the slot 14 and also serves as a guard or fender for the carrier 8.

After the soiled, cut or tangled yarn has 85 been unwound from the bobbin, the remainder of the yarn may be rewound upon any suitable form of winder.

The accumulation of yarn on the tapering carrier 8 may be slipped off whenever 90 desired.

I claim as my invention:

1. A waste winder having, in combination, a support, a rotary spindle carried by the support, a yarn carrier on the spindle, 95 and a stationary housing surrounding the yarn carrier and having a rear wall which is rigidly secured to the support, an open forward side, and a peripheral wall, said peripheral wall having a slot in its lower 100 portion for the passage to the yarn carrier of the thread being wound, said yarn car-

rier being tapered toward the forward end thereof.

2. A waste winder having, in combination, a rotatory shaft, a yarn carrier mounted on the forward end of said shaft, a peripheral flange on the rear portion of said yarn carrier, a housing surrounding the

yarn carrier, said housing comprising a peripheral wall and a rear wall, and an annular flange on the rear wall surrounding 10 the flange on the yarn carrier.

In testimony whereof, I have hereunto set my hand.

HOWARD D. COLMAN.

Copies of this patent may be obtained for five cents each, by addressing the "Commissioner of Patents, Washington, D.C."
